TURFING MECHANISM FOR SEWING MACHINES

Erskine E. Boyce, Gastonia, N. C., assignor to
The Boysell Company, Gastonia, N. C., a corporation of North Carolina

Original application January 12, 1932, Serial No. 586,204. Divided and this application April 19, 1934, Serial No. 721,385

3 Claims. (Cl. 112—79)

My present invention relates to turfing mechanism for sewing machines, particularly multi-needle or gang sewing machines; and this application is a division of my co-pending application, Serial No. 586,204, filed January 12th, 1932.

In my said co-pending application I have disclosed a machine embodying a carrier for a plurality of needle bars, with means to reciprocate the same to cause the needles to collectively pass thru openings in the bed over which a fabric is run; and on the one side of the bed there are a plurality of turfing members, one for each needle, comprising a part to catch the loops formed in the yarn when the needles penetrate the fabric, and a cooperating part to sever the loops to form tufts on said side of the fabric. Such a machine is particularly, though not exclusively, adapted for use in producing tufted bath mats, and the like.

20 The subject-matter of the present invention resides in the members for catching and severing the loops, or in other words, the tufting mechanism.

25 The principal objects of the present invention are to provide, first, a relatively simple and efficient construction and arrangement of turfing mechanism for gang sewing machines; second, a construction of turfing mechanism for multi-needle or gang machines affording a relatively close arrangement of the turfing mechanism or members whereby the rows of tufts will be compact; and thirdly, to provide for simultaneous or collective operation of a great number of tufting members whereby mats may be progressively formed with a tufted area extending from side to side, with or without patterns, as disclosed in my said co-pending application, of which this is a division.

40 All of the objects and advantages of the invention will become more apparent and will be pointed out during the detailed description of the accompanying drawings, wherein is shown a preferred embodiment of the invention, and in which

45 Fig. 1 is a front elevation, partly in section, and with parts broken away showing the frame, needle carrier and turfing mechanism with the actuating parts therefor;

Fig. 2 is a view taken on the line 2—2 of Fig. 1; and

Figs. 3 and 4 are fragmentary sectional views, similar to Fig. 2, showing the mechanism in other positions;

50 Fig. 5 is a side elevation on a reduced scale of a sewing machine embodying the invention

and showing the means for progressively feeding the fabric;

Fig. 6 is a front elevation of the machine shown in Fig. 5; and

Fig. 7 is a fragmentary enlarged elevation of the actuating means for the cloth feed.

Referring to Fig. 1, the numeral 5 designates a plurality of needle bars each having a stem 6, provided with needle receiving openings or sockets in their lower ends, and screws 7 tapped through the stems to retain the needles 8. The needle bars are mounted on a carrier 11, the ends 12 of which are slidably mounted on tracks 13, which are secured at opposite ends to uprights 14 by bolts 15. The uprights 14, may be held in place by angle irons 16, secured to the supporting frame 17, by bolts 18.

A shaft 20 is journaled on the frame for rotation by any suitable mechanism, such as hereinafter described, and carries at spaced intervals, 20 preferably adjacent the ends of the frame 11, eccentrics 21, which receive the ends 22 of rods 23, the other ends of which are pivotally connected by stub shafts 24 to couplings 25, which may be adjustably connected to the carrier 11 by bolts 26 extending through slots 27 in the couplings and through the carrier 11.

A plurality of disks 28, each carrying a cam 29 (Fig. 2) are mounted on the shaft 20, and the cams 29 engage arms 30 of members 31, the upper ends of which are secured to a beam 32 as by bolts 33, so that as the shaft 20 is rotated, the cams 29 and associated parts effect a reciprocating motion of the beam 32, which extends across the machine below the bed over which the fabric moves. At the same time, as explained in detail in my co-pending application, the eccentrics 21 and associated parts effect a reciprocating up-and-down motion of the carrier 11. The relative motions of the beam 32 and the carrier 11 are such that the beam 32 will be moving to the left of the position shown in Fig. 2 as the carrier 11 descends, and vice versa.

The beam 32 is in substance an actuator for the turfing mechanism, which includes a plurality 45 of similar loop catching and severing elements about to be described. Each of these elements comprises a finger or loop catching element 34, movable with the beam 32, and being provided with a hooked beak or end 35, and a cutting edge 50 therebehind. Obviously the reciprocating movement of the beam 32 transversely to the path of the movement of the needle bars and needles causes the hooked ends 35 of the members 34 to pass across the path of movement of the nee- 55

dles so that as hereinafter pointed out in detail, the loops formed on the underside of the fabric will be caught on the members 34 by the beaks 35 as the needles ascend. There is one loop-receiving member 34 for each needle and the same are arranged or positioned substantially in alignment with the needles so as to receive the loops formed by the needles when they pierce the fabric. The loop-receiving members 34 each have extensions 36 (Fig. 3) received in slots in the beam 32 and in which they may be held by an elongated plate or bar 37 secured to the beam by pins 37'.

A cutting blade 38 is pivotally connected at 39 to each of the members 34, each of said blades being provided with a depending arm or extension 40 adapted for connection with a support by any suitable means affording the necessary movements hereinafter explained. Such connection may be made by providing the lower end of the arm 40 with a notch 41 to receive the flange 42 of a plate 43 held in fixed position by rods 44, which may be connected to a plate or part 45 of the bed support by nuts 46 engaging the inner and outer faces of the said plate or part 45; the rods of course having threaded ends extending through the part 45 to receive the nuts.

Preferably the plate 45 has a top flange 48, and a similar plate 49 has a corresponding flange 50 in alignment with the flange 48, between which the loop retaining and severing members operate. Cross bars 51, to which the members 31 are fulcrumed as at 31', are secured between, the plates 45 and 49, as by bolts and nuts 52. The bed plate 53 over which the fabric is moved by any suitable mechanism, is mounted on blocks or elongated plates 54 on top of the flanges 48 and 50. The bed plate 53 is provided with a plurality of openings 55, each aligned with a needle and through which the needles pass after they pierce the fabric.

It should be obvious from the foregoing that each time the eccentrics 21 and rods 23 move the needle carrier 11 down, the needles will pierce the fabric and pass through the openings 55, while at the same time the cams 29 actuate members 31 to move the beam 32 and the members or fingers 34 toward the needles so that the said members or fingers 34 pass through the loops formed in the yarn beneath the bed and fabric to retain the loops when the needles are moved up by the carrier 11. During the upward movement of the carrier 11, the beam 32 moves in reverse direction to the position shown in Fig. 2, so that the beaks or hooks move back from the needles. During the movement of the beam 32 toward the needles the blades 38 rock on their pivots 39 so that their cutting edges move away from the cutting edges of the members 34, and during the reverse movement of the beam 32 away from the needles the blades 38 rock reversely on their pivots 39 so that the cutting edges thereof come into cutting relation with the edges of the members or fingers 34 to sever loops carried by the fingers.

It should be obvious that the relative length of the fingers and the blades can be varied, whereby the loops just caught will not be severed until they have been moved back by the succeeding loops. In other words, the first one or two loops caught will be carried on the members 34 during reciprocating movement thereof without being severed until a third or even fourth loop has been caught. Of course this is optional.

From the foregoing it should be apparent that the cutting action of each of the tufting parts is like that of a scissor, and that the action of the tufting parts is collective. In other words each movement of the beam 32 toward the needles effects catching of as many loops as are formed on the underside of the fabric when the needles penetrate the same, and the reverse movement of the beam effects cutting of all of these loops collectively. By making the blades 38 and fingers 34 of strong steel and relatively thin, it is possible to arrange them close together for the reason hereinabove mentioned.

In my said co-pending application, of which this is a division, I have shown and described in detail, mechanism for selectively latching and unlatching the needles so as to form untufted areas of predetermined patterns on a succession of mats, but I do not deem it necessary in this application to again refer to all of the aforesaid parts in detail, for obviously the present invention may be practiced on a gang machine, that is, a machine having a plurality of needles simultaneously penetrating the cloth to form the loops, whether the needles be latched or unlatched selectively to form untufted areas or not. The mechanism for selectively latching and unlatching the needles is shown in the drawings in dot and dash lines exactly as shown in full lines in my said co-pending application and as described therein.

In Figs. 5 and 6 I have shown the means for feeding the cloth C from a drum D across the bed of the machine and over rollers R to the feed roller F. The drum D is provided with a pulley P, in the groove of which is disposed a rope or cable J anchored at one end to a fixed bracket K and attached at its other end to a weight W to provide a frictional restraint on the rotation of the drum D.

Also in Fig. 5 I have shown a motor M connected with a pulley V to drive the belt U, which is also trained around a pulley Y to actuate the shaft 20 above referred to in connection with the tufting mechanism. The eccentric 56 is mounted on shaft 20 and receives the end 51 of rod 58, the other end of which is disposed against ratchet wheel 59 on shaft 60. A gear wheel 61 is keyed on shaft 60 and meshes with gear wheel 62 on a shaft 63 which rotatably carries the roller 64 preferably roughened to frictionally engage cloth C. A roller or rod 65 on frame 66 is disposed in front of the roller 64 to press the cloth against the face of the roller, and the cloth can be fed thereover from under the roller 64 to expose the tufted face of the cloth for ready inspection at all times during the tufting operation. A pawl or keeper 67 is pivoted at 68 to the frame to prevent backward movement of the wheel 59. The eccentric 56 is so positioned on the shaft 20 relative to the eccentrics 21 and cams 29 that the rod 58 receives a forward motion to thrust against one of the teeth on wheel 59 after the needle carrier has ascended to remove the needles from the cloth. It should be apparent that the forward thrust of the rod slightly rotates wheel 59, shaft 60, gears 61 and 62 and roller 64, which latter being in frictional engagement with the cloth will move it across the bed of the machine. The ratio of gears 61 and 62 can determine the length of feeding movement imparted to the cloth.

Obviously the apparatus herein described may be used in connection with mechanism such as

shown either in my said co-pending application, Serial No. 586,204 or my co-pending application Serial No. 666,208 to form mats with untufted areas to be later filled in on single sewing machines with tufts of a contrasting nature or color. The advantage of the present invention being that the mats may be formed in a succession on a strip of fabric of relatively great length, and each time the needles descend they form the loops simultaneously from one side of the fabric to the other, which loops are also collectively severed to form the tufts across one dimension of the mat, and each time the needles ascend the feed mechanism is actuated to move the fabric a predetermined distance to receive another line of tufts.

I claim:

1. In a multiple needle sewing machine for tufting fabrics, a carrier for a plurality of needle-bars, means latching the needlebars to the carrier for movement therewith, a plurality of loop-receiving members one for each needle and each including a finger movable back and forth in a path intersecting the path in which the needle-bar reciprocates, said finger having a cutting edge, a blade pivotally connected to each of said members and having a cutting edge co-operating with the cutting edge of said finger, said pivoted cutting blade having a depending portion, a support on which the depending portions are fulcrumed, and means to collectively move said fingers to cause all of said cutting blades to be

moved into and out of cutting relation with the cutting edges of the fingers solely by the movement of said members.

2. Tufting mechanism for a sewing machine having a plurality of needle bars and a carrier to collectively reciprocate the said needle bars and needles therein to cause the needles to collectively pierce a fabric and form loops on one side thereof, a plurality of loop retaining members on said side of the fabric to catch the loops formed by the needles, a mounting for said members, means to move said mounting and members toward the needles when they pierce the fabric and away from the needles when they ascend, a plurality of cutting blades one pivotally connected to each of said members and collectively operable by movements of said mounting to collectively sever the loops on said members.

3. Tufting mechanism for gang or multiple needle sewing machines comprising an elongated mounting, means to reciprocate said mounting, a plurality of loop receiving fingers carried by said mounting in alignment with the needles, a plurality of cutting blades each pivotally supported adjacent one end, a support pivotally connected to the cutting blades adjacent their other ends, said first pivotal connection being moveable with and by the mounting and said second pivotal connection being fixed to collectively move the cutting edges of the blades with respect to the fingers during reciprocation of the mounting.

ERSKINE E. BOYCE.
